UNITED STATES PATENT OFFICE.

HENRY F. READ, OF BROOKLYN, NEW YORK.

WRENCH.

SPECIFICATION forming part of Letters Patent No. 241,881, dated May 24, 1881.

Application filed October 25, 1880. (No model.)

To all whom it may concern:

Be it known that I, HENRY FRANKLIN READ, a citizen of the United States, residing at Brooklyn, in the county of Kings and State of New York, have invented new and useful Improvements in Wrenches, of which the following is a specification.

My invention relates to that style of wrenches embraced in my patent dated May 13, 1873, and in which the holding device for the sliding jaw is of two separate parts, connected in a manner to allow the holding toothed part to move over the screw-stem to release the lock of the sliding jaw. In this movement of the holding part it is liable to catch and bind upon the end of the screw-stem, and thus make it somewhat difficult to free the holding device from the teeth of the jaw-bar to move the sliding jaw.

My present improvements are designed to remedy this objection, to render the wrench more effective and easily and conveniently operated, and to reduce the expense of manufacture. I make the holding device practically of one piece, so that the screw-stem moves with it in separating the locking-teeth; and to allow of such movement of the screw-stem the nut thereon has a fulcrum-bearing in the sliding jaw, or a bearing similar to a ball-and-socket joint, so that the nut is free to move with its screw-stem toward and from the toothed jaw-bar upon said bearing in operating the holding device.

Referring to the accompanying drawings, Figure 1 represents my improved wrench in longitudinal section; Fig. 2, the holding device detached, showing the screw-stem and its thumb-strap rigidly connected; Fig. 3, the sliding jaw detached, showing the convex form of the forward seat for the thumb-nut; Fig. 4, the thumb-nut detached, showing its angular shouldered grooves and its convex bearing end. Figs. 5 and 6 show the claw-wrench; and Fig. 7, a section of the thumb-nut holding device, and sliding jaw united.

The jaw-bar *a* has the usual fixed jaw, *b*, and is provided with teeth *c* on one side, into which the holding device locks, and it has the usual handle. The sliding jaw *d* is fitted for movement upon the jaw-bar, and the holding device

is connected with said sliding jaw, and is also 50 fitted for sliding movement upon said bar.

The holding device consists of the screw-stem *e*, upon the inner side of the shank of which are formed teeth *f*, which interlock with those of the fixed jaw-bar, and the thumb-operating strap *g*, which latter embraces said bar, 55 said screw-stem and strap being rigidly connected to each other with thumb-surface *g'*, corrugated to give the proper hold in operating the sliding jaw. The sliding jaw is formed 60 with a projection, *h*, through which the screw-stem passes, and between this projection and the jaw proper the thumb-nut *i* is placed, and into the screw-threaded opening of which said screw-stem works to effect the clamping action 65 of said jaw on the article to be operated upon.

The seats for the thumb-nut are of peculiar construction—the one, *j*, upon the back of this jaw being a convex projection, and the other, *k*, on the inner side of the projection *h*, being a 70 concave recess—and through the seats thus formed the screw-stem passes. The ends of the thumb-nut are of corresponding form with its seats—that is to say, the concave end of said nut is adapted to fit snugly upon the convex 75 jaw-seat *j*, and to have a movement thereon similar to that of a ball-and-socket joint, while the convex end *k* of said nut fits snugly within the concave seat, whereby said nut is allowed to have a movement with and controlled by the 80 holding device toward and from the fixed jaw-bar. The opening in the jaw-bar projection *h* for this purpose is of sufficiently larger size than that of the screw-stem to allow such movement, which is to make and release the 85 locking action of the holding device with the teeth of said bar by separating the teeth sufficient to allow them to pass each other, thereby rendering such action convenient and under 90 easy control in sliding the jaw, because by reason of this capacity of the thumb-nut to move with the holding device toward and from the bar it matters not how the thumb is applied to said holding device.

To maintain the locking action of the holding device a spring, *l*, is applied thereto, preferably for action upon the under side of the jaw-projection *h*, through which the screw-stem

passes, and on the outer side of said stem, because such arrangement is advantageous as being free from friction, as it does not slide upon the bar with the jaw. The spring is permanently secured at one end within a recess formed in the shank of the screw-stem, and covered by a cap which protects it from dirt and corrosion. The inner end of the screw-stem has no threads, and enters a corresponding hole in the sliding jaw, and is provided with a shouldered recess, *m*, into which a pin, *n*, or screw, inserted through the jaw, fits, merely to act as a stop to prevent the possible separation of the parts, while the function of the recess *m* is to allow of the movement of the jaw upon said screw-stem for a given distance to effect the clamping action of the jaw. This clamping action cannot be made effective for general purposes by the action of the fingers upon a milled nut, and I therefore provide the nut with parallel grooves *s*, extending from end to end, the sides of which are angular or radial, for the purpose of allowing the use of a claw-wrench, *v*, adapted to fit into said grooves and over the nut, to produce an excessive clamping power of the sliding jaw upon the thing to be clamped, so that the wrench can be used for any clamping purposes, and it is put on without the exercise of any special care, as the claw *r* is sure to catch into the grooves and to be securely held therein against the angular shoulder and give the desired leverage. This claw-wrench is shown at *A*, with the claw long enough to take a good hold.

I have shown and described the seats for the thumb-nut as being of convex and concave form; but I do not confine myself to such specific construction, as it is obvious that the object and advantages aimed at—viz., the movement of the thumb-nut by and with the holding device in relation to the bar and the bearing of said nut upon the movable jaw—may be effected by different means from the specific construction shown. The thumb-nut with the square-shouldered grooves gives important advantages in a wrench having a sliding jaw operated by a screw-stem.

I have stated that the screw-stem *e* and the strap *g* are rigidly connected together, and it is preferable to weld them together in a manner

to render them practically integral, though not of a single piece.

I claim—

1. In combination, the toothed jaw-bar, the sliding jaw and the holding device therefor, the nut upon the screw-stem of said holding device, having a concave end, and the sliding jaw having a convex seat for said nut, substantially as described, for the purpose specified.

2. In a wrench, the combination of the toothed jaw-bar, the sliding jaw, the holding device therefor, consisting of the rigidly-connected toothed screw-stem *e* and the strap *g* and the nut *i*, the said sliding jaw having a convex and a concave seat, and the nut having corresponding concave and convex ends fitting said jaw-seats, substantially as described, for the purpose specified.

3. The sliding-jaw-holding device, consisting of the screw-stem *e*, provided with the toothed shank and the thumb-operating strap *g*, rigidly connected to each other, in combination with the thumb-nut, the sliding jaw, and the spring, constructed for operation substantially as set forth.

4. The combination of the spring *l*, arranged upon the toothed shank of the screw-stem *e*, with the open sliding-jaw part *h*, upon which said spring acts, and the toothed jaw-bar *a*, the opening in the said part *h* being sufficiently larger than the screw-stem to afford lateral movement thereof in relation to said toothed bar, substantially as described, for the purpose specified.

5. The combination, in a wrench, of the fixed and the sliding jaws with the holding device, consisting of rigidly-connected screw-stem and strap, a spring carried by said holding device, and the thumb-nut having a movement controlled by that of the holding device to separate the locking-teeth, substantially as 90 and for the purpose specified.

In testimony whereof I have hereunto set my hand in the presence of two subscribing witnesses.

HENRY F. READ.
